PNEUMATIC THREAD HOLDER FOR MULTI-STACK MAGAZINES

George N. Peterson, Grafton, Mass., assignor to
Crompton & Knowles Loom Works, Worcester,
Mass., a corporation of Massachusetts

Application April 2, 1947, Serial No. 738,861

11 Claims. (Cl. 139—247)

1

This invention relates to weft replenishing looms and it is the general object of the invention to provide a pneumatic thread holder adaptable more particularly to reserve bobbin magazines having plural groups or stacks of bobbins.

Weft replenishing looms of the multicolor type usually have two or more bobbin stacks from which extend groups of weft ends which should be kept taut for successful loom operations. It is also necessary to be able to remove the thread of a freshly transferred bobbin when cut at the selvage. Pneumatic thread holders as generally made permit the threads or weft ends to become entangled with each other in such manner as to prevent prompt removal of the threads when cut at the selvage.

It is an important object of the present invention to provide means which cause the weft ends to enter the intake mouth in separate groups with each thread spaced from all the other threads entering the mouth.

It is another object of the invention to provide a thread separator and thread guide which cause the threads to divide automatically into their respective groups when drawn toward the intake mouth incident to placement of fresh bobbins in the magazine.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a side elevation partly in cross section of a weft replenishing loom having the invention applied thereto.

Fig. 2 is an enlarged front elevation of the thread holder looking in the direction of arrow 2, Fig. 1.

Fig. 3 is a plan view looking in the direction of arrow 3, Fig. 2.

Fig. 4 is a side view looking in the direction of arrow 4, Fig. 3.

Figs. 5, 6 and 7 are vertical sections on lines 5—5, 6—6 and 7—7, respectively, of Fig. 4.

Fig. 8 is a horizontal section on line 8—8, Fig. 2.

Fig. 9 is a section on line 9—9, Fig. 5, and

Fig. 10 is a diagrammatic plan view showing how threads are automatically separated into their respective groups when placed downwardly into the thread holder.

Referring to Fig. 1, the loom frame 10 supports a reserve bobbin magazine M which in the present instance holds two groups of bobbins 11 and 12 from which extend groups W and W' of weft

2

ends, one at the front and the other at the back of the magazine. The weft ends lead to a pneumatic thread holder H to be described in detail hereinafter. An air pump 13 supported by the loom and operated by the lay 14 is connected to a forwardly extending hose 15 leading to a hollow thread collector 16 associated with holder H. A stand 17 secured to the loomside affords support for the collector and holder.

10 At the time of a replenishing operation a transfer arm 18 pushes a bobbin from the magazine into a shuttle 19 which is then picked to the opposite side of the loom. The thread of the transferred bobbin is eventually cut at the selvage and drawn into the holder H and thence to collector 16.

The matter thus far described is of common construction and may if desired be made as set forth in prior patent to Turner No. 2,199,353.

20 In carrying my invention into effect a forward extension 20 of the thread collector has a tube 21 held therein in angularly adjusted position by set screw 22. The holder H includes front and back horn members 23 and 24, respectively, the latter of which is secured to tube 21 by set screw 25. Front and back blocks 26 and 27 are spaced by a thread separator plate 28, see Fig. 8, and the front horn, both blocks and plate 28 are all secured to the back horn by screw 29. The blocks 30 are preferably though not necessarily below the bottom of tube 21, see Figs. 5 and 6.

Tube 21 has extending therethrough a thread passage 35 shaped more or less as shown in Figs. 6 and 7. This passage has a surface 36 arcuate and convex toward the magazine M. A second surface 37 spaced from surface 36 and extending generally in the same direction may be planate, and the surfaces 36 and 37 are joined by narrower upper and lower surfaces 38 and 39, respectively.

40 Surface 36 is so disposed that all the threads of group W' leading from the rear stack of bobbins and drawn pneumatically into passage 35 will engage some part of it and be separated from each other along the curved surfaces, as shown in Fig. 6.

45 Separator or thread dividing plate 28 is made substantially as shown in Fig. 5, and has a curved thread engaging edge 40 concentric with surface 36 but located a little farther from the magazine. Surface 40 is disposed similarly to surface 36 in that all the threads of group W engage it and are spaced along its length. Fig. 9 shows how curved edge 40 causes the group W to extend along passageway 35 spaced from group W'.

55 Plate 28 has an upper surface 42 extending up-

wardly from edge 40 toward the magazine and extends beyond adjacent parts of the horns 23 and 24 to provide a baffle 43 which projects below the horns. The lower ends of horns 23 and 24 define between them a narrow air space 45 divided into front and back compartments 46 and 47, respectively, by plate 28.

Horns 23 and 24 have facing inclined surfaces 50 and 51, respectively, which diverge upwardly from thread space 45. These horns also have surfaces 52 and 53 which may be in the same plane and are inclined downwardly and generally toward the magazine. Both sets of inclined surfaces terminate above the plate 28 as shown in Figs. 4 and 5, although this is not an essential relation, and top edge 42 has its high point a nearer the magazine than are adjacent parts of the horns, see Figs. 5 and 10.

Fig. 10 illustrates the reasons for the relationships just described. When new bobbins are placed in the magazine their weft ends are drawn toward the holder and passed down between the horns 23 and 24. The rearmost position which can be assumed by any thread in group W is indicated by the light dot and dash line b which passes in front of point a on plate 28. As this thread slides down surface 51 it descends along edge 42 and slips under cusp like point 55 between edges 42 and 40 to the heavy dot and dash line c, and when released will be drawn around the latter edge and into passage 35. Obviously, a thread from group W sliding down surface 50 of the front horn will not need to be guided by edge 42.

Similarly, a thread from rear group W' engaging the horn 50 in the position of light solid line d, Fig. 10, will slide down surface 50 and be behind point a on plate 28. As this thread moves to the heavy solid line position e it will be drawn into passage 35 along surface 36 when released. Point a is thus seen to be so located relatively to the horns and the directions in which the threads approach holder H from the magazine that the threads are automatically separated to lie in the corresponding compartment 46 or 47.

From the foregoing it will be seen that the two groups of threads are separated by guide plate 28 and enter passage 35 along separate paths. Also, the threads of each group are separated from each other by the curved edges or surfaces which they engage. The plate 28 divides the space 45 into narrow compartments which by their proportions cause strong drafts of air to pass through them to hold the weft ends in the proper spaced relation. While a reciprocating air pump has been shown, the invention can also be used with a continuous suction. Furthermore, each thread when cut at the cloth selvage subsequent to transfer of the corresponding bobbin can be drawn promptly into passage 35 with little or no entanglement with adjacent threads. The top of plate 28, particularly the point a, relatively to the horns 23 and 24 permit an automatic separation of the threads into their proper groups when placed downwardly between the horns, as explained in connection with Fig. 10.

Having thus described my invention it will be seen that changes and modifications may be made therein by those skilled in the art without departing from the spirit and scope of the invention and I do not wish to be limited to the details herein disclosed, but what I claim is:

1. In a pneumatic thread holder for a weft replenishing loom having two groups of weft ends leading from a reserve bobbin magazine, thread holder means containing a thread passage trans-

verse of said weft ends and within which subatmospheric pressures exist, said passage having a thread intake mouth formed with a curved surface convex toward the magazine and along which the weft ends of one of said groups are distributed, and guide means fixed with respect to said holder means spaced from said passage and having a curved edge convex toward the magazine and farther from the latter than is said curved surface and along which the weft ends of the other groups are distributed and from which the second group enters said passage spaced from the first group.

2. In a pneumatic thread holder for a weft replenishing loom having two groups of weft ends leading from a reserve bobbin magazine, thread holder means containing a thread passage transverse of said weft ends and within which subatmospheric pressures exist, said passage having a thread intake mouth formed with a curved surface convex toward the magazine and along which the weft ends of one of said groups are distributed, and guide means fixed with respect to said holder means spaced from said mouth and having a curved edge convex toward the magazine and aligned with part of said passage spaced from said curved surface in a direction away from the magazine and along which the weft ends of the other group are distributed and from which the second group enters said passage.

3. In a weft replenishing loom having a reserve bobbin magazine from which front and back groups of weft ends extend, a pneumatic thread holder including a tube within which subatmospheric pressures exist, said tube having a thread intake mouth the side of which nearest to the magazine is curved and convex toward the magazine, the weft ends of the back group being distributed along said curved side of the mouth and entering said mouth and tube, and a plate spaced forwardly from the mouth and having a curved edge convex toward the magazine along which the weft ends of the front group are distributed and from which said front group extends into said mouth and tube along paths beyond said curved side of the mouth with respect to the magazine.

4. In a weft replenishing loom having a reserve bobbin magazine from which front and back groups of weft ends extend, a pneumatic thread holder including a tube within which subatmospheric pressures exist and having a thread intake mouth facing transversely of the weft ends, the side of the mouth nearest to the magazine being curved and convex toward the magazine and having the weft ends of the back group distributed therealong, and a guide having a curved edge concentric with said side of the mouth but farther from the magazine along which the weft ends of the front group are distributed and from which the front group enters the mouth spaced from the back group.

5. In a weft replenishing loom having a reserve bobbin magazine from which front and back groups of weft ends extend, a pneumatic thread holder including a tube within which subatmospheric pressures exist, two spaced thread guides having curved edges convex toward the magazine and at different distances from the magazine, the weft ends of the back group being distributed along one of said edges and entering the tube from said one edge, and the weft ends of the second group being distributed along the other curved edge and entering the tube from said other edge and spaced from the first group.

6. In a weft replenishing loom having a reserve bobbin magazine from which front and back groups of weft ends extend, a pneumatic thread holder including a tube within which sub-atmospheric pressures exist and having a thread intake mouth, two spaced members defining between them a thread space communicating with the mouth and extending toward the magazine and receiving the two groups of weft ends, and a guide in said space dividing the latter into front and back compartments, the back group entering the back compartment and entering the mouth directly therefrom and the front group entering the front compartment and extending partly around said guide and across the back compartment and then entering the mouth.

7. In a weft replenishing loom having a reserve bobbin magazine from which front and back groups of weft ends extend, a pneumatic thread holder including a tube within which sub-atmospheric pressures exist and having a thread intake mouth, spaced members defining between them a thread space communicating with the mouth and extending toward the magazine and receiving the two groups of weft ends, a guide in said space dividing the latter into front and back compartments, the back group entering the back compartment and entering the mouth directly therefrom and the front group entering the front compartment and extending partly around said guide and across the back compartment and then entering the mouth, said guide being so located as to cause said front group to enter said mouth spaced from the back group in a direction away from the magazine.

8. In a weft replenishing loom having a reserve bobbin magazine from which front and back groups of weft ends extend, a pneumatic thread holder including a tube within which sub-atmospheric pressures exist and having a thread intake mouth, front and back spaced members defining between them a thread space communicating with said mouth and extending toward the magazine, and a guide between said members dividing the space into front and back compartments, the weft ends of the back group entering the back compartment and bending laterally to enter said mouth directly and the weft end of the front group entering the front compartment and bending laterally around said guide and extending across said back compartment and then entering the mouth.

9. In a weft replenishing loom having a reserve bobbin magazine from which front and back groups of weft ends extend, a pneumatic thread holder including a tube within which sub-atmospheric pressures exist and having a thread intake mouth, front and back spaced members

defining between them a thread space communicating with said mouth and extending toward the magazine, and a vertical separator between said members lying between said groups of weft ends and having a top edge inclined upwardly and toward the magazine, weft ends drawn from both of said groups when moved down between said members engaging said separator and being separated thereby into their respective groups, one for said back compartment and the other for said front compartment.

10. In a weft replenishing loom having a reserve bobbin magazine from which front and back groups of weft ends extend, a pneumatic thread holder including a tube within which sub-atmospheric pressures exist and having a thread intake mouth, front and back spaced vertical members defining between them a thread space communicating with said mouth and extending toward the magazine, and a guide between said member dividing the space into front and back compartments, said guide having a top edge inclined upwardly and toward the magazine, a weft end derived from either group when moved down along the member corresponding to the other group engaging said top edge and being deflected thereby toward the compartment corresponding to the weft end.

11. In a weft replenishing loom having a reserve bobbin magazine from which front and back groups of weft ends extend, a pneumatic thread holder including a tube within which sub-atmospheric pressures exist and having a thread intake mouth, front and back spaced vertical members defining between them a thread space communicating with said mouth and extending toward the magazine, and a guide between said member dividing the space into front and back compartments, said guide having a top edge inclined upwardly and toward the magazine, a weft end of the back group when moved down along the front member engaging said top edge and being deflected thereby toward the back compartment, and a weft end of the front group when moved down along the back member engaging said top edge and being deflected thereby toward the front compartment.

GEORGE N. PETERSON.
